CLAIM

The ornamental design for an assembled razor handle and caddy, as shown and described.

DESCRIPTION

FIG. 1 is a right side elevational view of the assembled razor handle and caddy, the left side view being a mirror image of the side shown;

FIG. 2 is a right front perspective view thereof;

FIG. 3 is a front view thereof;

FIG. 4 is a top view thereof; and,

FIG. 5 is a perspective view of the rear thereof.

The structure shown in broken lines in the drawings is for illustration purposes only and form no part of the claimed design.
